United States Patent Office.

GEORGE PADDINGTON AND WALTER F. CREW, OF WAUBECK
IOWA.

Letters Patent No. 91,258, dated June 15, 1869.

IMPROVED HAMES-STRAP.

The Schedule referred to in these Letters Patent and making part of the same.

To whom it may concern:

Be it known that we, GEORGE PADDINGTON and WALTER F. CREW, of Waubeck, in the county of Linn, and State of Iowa, have invented a new and useful Improvement in Hames-Straps; and we do declare that the following is a true and accurate description thereof, reference being had to the accompanying drawings, and to the letters of reference marked thereon, and being a part of this specification.

The nature of this invention relates to an improvement in hames-straps; and consists in the peculiar arrangement of the plates and spring.

A, in the drawings, represents a proper plate, provided with guides D, through which passes the plate C, the same being perforated, as shown.

B is a spring, secured, at one end, by screw F, or otherwise, to the guides, and is provided with a tongue, which is designed to engage with the holes in the plate C, and hold the same firmly in position.

The outer ends of the plates A and C, are provided with hooks, rings, or other devices, by means of which they are attached to the hames.

Whenever it becomes necessary to unfasten the hames, raise the spring with its tongue out of its engagement with the holes in plate C, when the said plate may be drawn from the guides.

E is a thumb cam-latch, pivoted in one side of the guide D, and so arranged, that when rotated in one direction, its latch will pass over and press the spring B down in place, and when rotated in the opposite direction, will pass under and raise up the spring, disengaging its tongue from the perforations in the plate C below it.

What we claim as our invention, and desire to secure by Letters Patent, is—

The arrangement of the plates A and C, guides D, spring B, and cam-latch E, when combined and operating substantially as and for the purposes herein set forth.

GEORGE PADDINGTON.
WALTER F. CREW.
